UNITED STATES PATENT OFFICE

RAYMOND WARE, OF ITHACA, NEW YORK

INTERNAL-COMBUSTION ENGINE

Application filed May 24, 1927. Serial No. 193,939.

This invention relates to engines of the sleeve valve type, particularly to internal combustion engines having a single sleeve valve which, in addition to rotation, receives 5 a relatively slight reciprocation, although certain features of the mechanism are adapted for use in engines in which the sleeve valve rotates only.

Mechanism for imparting both movements 10 to sleeve valves are disclosed in my prior Patents, No. 1,107,468 of August 18, 1914, and No. 1,453,815 of May 1, 1923, and the present invention comprises an improved mechanism for accomplishing the same purpose, especially 15 in radial type engines. It is particularly applicable to radial engines of aircraft, owing to its compactness, simplicity, durability and lightness.

The improvement will now be described in 20 connection with the accompanying drawings, illustrating an embodiment of the invention in a multi-cylinder radial air-cooled engine. In said drawings:

Fig. 1 is a central longitudinal section 25 through one cylinder and the crank case;

Fig. 2 is a side view on a larger scale, taken at right angles to Fig. 1, of one cylinder showing the cylinder head in section and the top of the crank case only, and

Figure 3 is a cross sectional view taken on the line 3—3 of Fig. 2.

As shown in these views, the cylinder 1 is provided with cooling fins 2, as is the cylinder head 3, carrying the spark plugs 4 and having 35 a skirt 5, fitting in the sleeve valve 10. The skirt 5 is cut away on one side, as shown by lines 6 in Fig. 2 and, as appears more clearly in Fig. 3, the cut-away portion exposes the cylinder inlet port 7 and exhaust port 8. As 40 shown, see Fig. 3, these ports are located 180° apart, but this is not essential. The head is internally hemispherical, as shown at 9, and constitutes the combustion chamber. This type of cylinder head forms the subject matter 45 of another application for patent filed by me on September 19, 1924, as Serial No. 738,622, now Patent No. 1,657,490, and its advantages, therefore, need not be set forth at length herein.

50 The piston 11 is connected by the rod 12 to

the crank throw 13 of the crank shaft 14, journaled in the crank case 15. The pistons in the other cylinders, which may be from 3 to 9 in number, are also connected to said crank throw in the usual manner.

55

In the crank case, adjacent and parallel to the crank throw 13, is fitted a bearing supporting plate 16, and a web 17 projects inwardly from the conical front plate 38 of the crank parallel to said bearing plate, to carry 60 additional bearings, to be later described. Each cylinder flange 18 is secured to the crank case by studs 19 and, at one point, between said flange and the crank case the flattened stem 20 of a journal pin 21 is clamped by the stud 22. On each of said pins and in a recess in each cylinder wall is rotatably mounted a roller 23, constituting part of the means for reciprocating the sleeve valves 10. The periphery of the plate 16 is clamped between the 65 end of the crank case and the front plate 38.

70

Each sleeve valve, which has a single port 39, is enlarged or flanged at its inner end, the rear shoulder of said enlargement or flange constituting a substantially flat helical cam surface 24, on which the roller 23 bears. The periphery of said flange slopes inwardly and downwardly from the outer edge of said surface 24 to form an inclined or conical cam surface 25 having a similar helical inclination as the surface 24. The extreme inner end of each sleeve valve is provided with bevel gear teeth 26, which also have a similar helical inclination as the cam surfaces 24 and 25.

75

Peripherally journaled in the plate 16 is a large ring gear 27, provided with bevel teeth 28 in mesh with the teeth 26; with a concentric conical cam roller surface 29 in engagement with the cam surface 25, and with internal gear teeth 30, by which it is driven. A pinion 31 meshes with said teeth 30, and fast on the driving shaft 32 of the same is a gear 33, meshing with an idler 34, which, in turn, meshes with and is driven by a pinion 35, fast on the crank shaft 14. The shaft 32 of pinion 31, which constitutes the axles of gear 33, and the hub of the idler 34, are carried in ball bearings 36, mounted in the plate 16 and in the web 17, respectively.

80

85

90

95

100

The ratio of the gearing, just described, is such that the large ring gear 28 rotates at one-sixth the speed of the crank-shaft, and said ring gear 28, being three times the diameter of the valve bevel gear 26, the sleeve valves are driven at one-half the speed of the crank-shaft, so that said valves make one complete rotation for four strokes of the piston. Obviously the gear train may be varied, if desired, provided that the valves rotate at one-half the speed of the crank shaft. All the valve-actuating mechanism, being enclosed in the crank-case, is perfectly lubricated by the oil splashed thereon by the crank. The cam surfaces 25, 29, and 24 receive oil through the meshing teeth 26 and 28 as do the bearings of the rollers 23. The sleeve valves are provided with openings 37, through which oil passes between them and the cylinder walls. The cylinders can be removed, with their valves, by removing the nuts from the studs in the crank case and the plate 16, with the gearing carried thereby, can be removed from the crank case after the front plate 38 is taken off, to give access to the intermediate gearing, if necessary. There are no outside moving parts, and the overall dimensions of the engine for a given power are materially reduced. The ring gears 26, 28, may have spur teeth instead of bevel, if desired. If the sleeve valves are to rotate without any reciprocation, the cam surfaces 24 and 25 and the bevel ring gear 26 do not have any helical inclination but run at right angles to the axis of their respective cylinders, as will be obvious.

Having described the invention what is claimed is:

1. A radial engine having a sleeve valve in each cylinder, each valve having a flat and a conical cam surface and gear teeth on its inner end, a driving gear in the crank case in mesh with said gear teeth and having a conical roller surface in engagement with said

conical cam surfaces, and a guide mounted on the inner end of each cylinder and engaging said flat cam surface of the corresponding valve.

2. A radial engine having a sleeve valve in each cylinder, each valve having a flat and a conical cam surface and gear teeth on its inner end, said surfaces and teeth running obliquely to a plane at right angles to the valve and cylinder axis, a common driving gear, operatively connected to the engine crank shaft, meshing with said teeth and having a conical roller surface in engagement with said conical cam surfaces, and a roller journalled in each cylinder-wall and bearing on the flat cam surface of the corresponding valve.

3. In a radial cylinder engine having a single sleeve valve in each cylinder, each valve having a bevel ring gear and a conical cam surface on its inner end, said surface and the

pitch line of said gear running at an oblique angle to a plane at right angles to the axis of the valve, a single driving gear in mesh with all of said ring gears and having a concentric conical roller surface engaging all of said conical cam surfaces, means to maintain said gears in mesh and said surfaces in contact, and means operatively connecting said driving gear to the engine crank shaft.

4. In an internal combustion engine, the combination with the crank shaft and the cylinder having inlet and exhaust ports, of a single ported sleeve valve, in said cylinder, a substantially conical and a substantially flat cam surface on the lower end of said valve, a ring gear on said end, a roller journalled in the cylinder wall and engaging said flat cam surface, a driving gear in the crank case in mesh with said ring gear and having a conical roller surface engaging said conical cam surface, and means to drive said driving gear from said crank shaft.

5. In a radial engine, the combination with a plurality of cylinders and a common crank throw; of a driving gear operatively connected to said crank throw and having a conical roller surface on its periphery; a sleeve valve in each cylinder carrying gear teeth in mesh with said driving gear, a conical cam surface on each of said sleeves engaging said conical roller surface on said gear, each of said valves having a substantially flat cam surface adjacent said conical cam surface; a roller mounted on a fixed pivot at the inner end of each cylinder and engaging said substantially flat cam surface.

6. In a radial sleeve valve engine, means to rotate the valves, comprising gear teeth on the lower ends of the same, a bearing plate fitted in the crank case, a driving ring gear journalled at its periphery in said plate and meshing with said teeth, a pinion fast on the crank shaft and connections between said pinion and said gear.

7. In a radial sleeve valve engine, the combination with the cylinders, crank-shaft and crank case, of a bearing plate mounted in the crank case, an internal gear peripherally journalled in said plate and carrying external bevel teeth; a conjugate ring gear on the enlarged end of each sleeve valve, a roller for each valve bearing on the back of its enlarged end, a journal pin for each roller secured between the respective cylinder and the crank case, a pinion on the crank shaft, gearing intermediate said pinion and said internal gear, and journal bearings for said gearing carried by said plate.

8. In a radial cylinder engine, a single rotary and reciprocatory sleeve valve in each cylinder having a thickened inner end provided on one side with a substantially flat cam surface and on the other side with gear teeth and a conical cam surface, a roller for each valve journalled on a fixed support and en-

gaging said flat cam surface, a ring gear journaled in the crank case, meshing with said teeth and having a concentric conical roller surface at its periphery engaging said conical cam surfaces, and gearing operatively connecting said ring gear with the crank shaft.

9. In a radial cylinder engine, the combination with a sleeve valve in each cylinder, of a ring gear on the inner end of each valve, the latter being also provided with a conical cam surface adjacent said ring gear and with a substantially flat cam surface adjacent said conical surface, a driving gear in mesh with all of said ring gears, said driving gear being provided with a conical roller surface in engagement with said conical cam surfaces, and a roller for each valve carried on a fixed axis and engaging said substantially flat cam surfaces.

10. An internal combustion engine, comprising a plurality of radially arranged cylinders, a single sleeve valve in each of said cylinders, each valve having gear teeth around its inner end; a ring driving gear in mesh with said gear teeth of all the valves, whereby the latter are rotated, and means associated with said ring gear and said valves to reciprocate the latter during their rotation.

11. In a radial type internal combustion engine, the combination of a sleeve valve in each cylinder, each valve having gear teeth and two cam surfaces on its inner end, a driving gear in mesh with said teeth and having a roller surface engaging one of said cam surfaces of each of said valves, and a guide surface on the base of each cylinder adapted to engage the other of said valve cam surfaces.

12. In a radial engine, the combination with the cylinders, pistons, crank shaft and crank case, of a sleeve valve in each cylinder, gear teeth and a cam surface on the inner end of each valve, a supporting flange plate in the crank case, a driving gear mounted on said plate and meshing with said gear teeth, a surface on said gear engaging said cam surfaces, a removable front plate on the end of the crank case, gearing between the crank shaft and said driving gear, and bearings for said gearing in said flange and front plates.

13. In an internal combustion engine of the radial type, the combination with the crank case, of a supporting plate mounted therein, a common valve operating gear mounted concentrically on said plate, and means for driving said gear from the crank shaft.

14. In an internal combustion engine, the combination with the crank shaft and a cylinder having inlet and exhaust ports, of a sleeve valve in said cylinder having a substantially conical and a substantially flat cam surface at one end, a ring gear on said end, a guide at the base of the cylinder to engage said flat cam surface, a driving gear in the

crank case meshing with said ring gear and having a conical roller surface contacting with said conical surface on the valve, and means to drive said driving gear from the crank shaft.

In testimony whereof I have hereunto set my hand.

RAYMOND WARE.
